DESIGN FOR A DOUBLE-DECKER FOLDING TRAY

Michael Gargaro, Yeadon, and William Edward Jewell, Jr., Philadelphia, Pa.

Application June 28, 1947, Serial No. 139,990

Term of patent 3½ years

(Cl. D44—10)

To all whom it may concern:

Be it known that we, Michael Gargaro and William Edward Jewell, Jr., citizens of the United States, residing respectively at 974 MacDade Boulevard, Yeadon, Delaware County, Pennsylvania, and 1931 Seventy-Second Avenue, Philadelphia, county of Philadelphia, Pennsylvania, have invented a new, original, and ornamental Design for Double Decker Folding Tray, of which the following is a specification, reference being had to the accompanying drawing, forming part thereof.

We claim:

The ornamental design for a double decker folding tray, as shown.

MICHAEL GARGARO.

WILLIAM EDWARD JEWELL, JR.
